HEATING APPARATUS

Philip Gubson, Chicago, Ill.

Application March 28, 1947, Serial No. 737,883

1 Claim. (Cl. 122—20)

This invention relates to heating apparatus. More particularly, this invention relates to heating apparatus which may be employed in residences and other buildings for general heating purposes and also for heating water so as to provide a supply of hot water as and when needed in a residence or other building.

An object of the present invention is to provide a new and improved heating apparatus, which is relatively small, compact, simple and inexpensive in construction, and which may be employed in residences and other places for general heating purposes.

Another object of the invention is to provide a new and improved heating apparatus which includes a novel hot water heating coil unit embodied therein for providing a supply of hot water as and when needed in a residence or other building.

A further object of the invention is to provide in the new heating apparatus a novel device for controlling the supply of water to the heating element which is embodied in the new heating apparatus.

Other and further objects of the present invention will be apparent from the following description and claim and are illustrated in the accompanying drawing which, by way of illustration, shows a preferred embodiment of the present invention and the principles thereof and what I now consider to be the best mode in which I have contemplated applying these principles. Other embodiments of the invention embodying the same or equivalent principles may be used and structural changes may be made as desired by those skilled in the art without departing from the present invention and the purview of the appended claim.

In the drawings:

Fig. 1 is a central vertical sectional view, partly in elevation, through the new heating apparatus, showing the arrangement of the various parts embodied therein; and

Fig. 2 is an enlarged fragmentary sectional detail view of a float valve unit which is embodied in the new heating apparatus for controlling the supply of water to the heating unit which is embodied in the new heating apparatus.

A preferred and typical embodiment of the present invention is illustrated in the drawing, wherein it is generally indicated at 10, and comprises a welded and generally cylindrical steel tank or boiler 11 which includes a vertically extending side wall 12, bottom wall 13, and top

wall 14, the top wall 14 being preferably arched or curved convexly upwardly, as shown in Fig. 1 of the drawing.

An upwardly arched steel partition 15 extends across the interior of the boiler 11, below the midportion thereof, and is secured around its marginal edge to the side wall 12 thereof in any suitable manner, as by welding. This partition 15 divides the interior of the tank or boiler 11 into a lower compartment 16, which is defined by the side wall 12, bottom wall 13, and partition 15, and an upper compartment 17 which is defined by the side wall 12, top wall 14 and partition 15 as will be explained more fully herein-after, the upper compartment 17 of the tank or boiler 11 is divided into an upper steam zone 44 and a lower water zone 46, and the normal line of separation between these two zones 44 and 46 is indicated by the dotted line 45 in Fig. 1.

20 A water intake line in the form of a pipe 35, which may be connected to a municipal water system or other suitable source of water, opens into the lower area of the upper compartment 17 and is provided with a manually operable control valve 36 which is disposed adjacent the side wall 12 of the tank or boiler 11. A water return line in the form of a pipe 18 leads into the upper compartment 17 of the tank or boiler 11 and this water return pipe 18 has a portion 19 which extends downwardly into the upper compartment 17, adjacent the side wall 12, and terminates in a horizontally extending lower end portion 20. A steam outlet line in the form of a pipe 21 opens out of the top wall 14 of the tank or boiler 11 and may be connected to steam radiators arranged in a residence or like building with which the new heating apparatus is used.

25 A safety release valve 22, a steam pressure gauge 23, and a rheostat steam pressure control unit 24, all of which may be of any suitable and conventional design, are arranged upon the top wall 14 of the tank or boiler 11.

30 A steam-generating unit is arranged in the lower compartment 16 of the tank or boiler 11. This steam-generating unit comprises a welded and generally cylindrical steel water jacket, generally indicated at 26, which includes a side wall 27, a bottom wall 28, and a convexly upwardly arched top wall 29. A suitable heating unit 30 in the form of a plurality of apertured gas burner coils 31 is arranged in the lower compartment 16, immediately below the bottom wall 28 of the water jacket 26, and each of these apertured gas burner coils 31 has a fuel supply line

in the form of a gas inlet pipe 32 attached thereto. These gas inlet pipes 32 extend through a suitable opening or hand hole 33 which is provided therefor in the side wall 12 of the tank or boiler 11. A fume duct 34 opens out of the lower area of the lower compartment 16 and extends upwardly along the side wall 12 of the boiler 11 to a point above the top wall 14 thereof, as shown in Fig. 1, so as to allow the fumes formed by the combustion of the gas in the coils 31 to escape to the atmosphere.

A vertically extending pipe 37 is arranged centrally within the tank or boiler 11. This pipe 37 is preferably made of a main and upper section and a lower section interconnected by a coupling 76. The lower section 38 of this pipe 37 extends downwardly through an opening 40 which is formed centrally in the top wall 29 of the water jacket 26 and thence downwardly centrally through the water jacket 26. The lower section 38 of the pipe 37 rests upon the bottom wall 28 of the water jacket 26. As shown in Fig. 1 of the drawing, the lower section 38 of the pipe 37, which is disposed within the water jacket 26, is provided with a multiplicity of openings or apertures 39, for a reason which will be explained hereinafter.

As is also shown in Fig. 1 of the drawing, the upper section of the pipe 37 extends upwardly through an opening 41 which is arranged centrally in the arched partition 15 and thence upwardly into the upper compartment 17 of the boiler 11, its upper end portion 43 opening into the steam zone 44 of the upper compartment 17. As pointed out hereinbefore, the steam zone 44 is that portion of the upper compartment 17 which is disposed above the normal water line 45 in the upper compartment 17 and which normal water line 45 divides the upper compartment 17 into the upper steam zone 44 and the lower water zone 46 (Fig. 1).

A cylindrical metal sleeve or jacket 42 surrounds the major portion of the upper section of the pipe 37 which is disposed in the upper compartment 17 of the boiler 11 and a water-conducting and water-heating coil 47 surrounds and encircles the sleeve or jacket 42 on the outer side thereof. The lowermost convolution of the water-conducting and water-heating coil 47 is connected to a water inlet in the form of a pipe 48 which may be connected to a municipal water system, or other source of water, and the uppermost convolution of the water-conducting and water-heating coil 47 is connected to a hot water outlet pipe 49 which, in turn, may be connected to suitable faucets or other conveniences in the residence or the like in which the new heating apparatus 10 is installed.

The new heating apparatus 10 includes a float valve control unit which is generally indicated at 50, and which is disposed outwardly of the lower compartment 16 of the tank or boiler 11, adjacent the side wall 12 thereof. This float valve control unit 50 includes a substantially cylindrical casing 51 which includes a vertically extending side wall 52, a bottom wall 53, and a top wall 54. The lower area of the interior of the float valve casing 51 is connected, by means of a pipe 55, to the lower area of the water jacket 26. Thus one end of the pipe 55 is attached to the bottom wall 53 of the casing 51 and the other end of the pipe 55 is attached to the side wall 27 of the water jacket 26 immediately above the bottom wall 28 thereof.

The float valve control unit 50 includes a movable float valve unit 56 which is movably mount-

ed in the float valve housing or casing 51. This float valve unit 56 includes a valve stem 57 which has a movable valve element 58 mounted thereon at the top thereof and the float valve unit 56 also includes a buoyant member or float 59 which is mounted upon the lower end portion of the valve stem 57 (Fig. 1). The movable valve element 58 of the float valve control unit 50 is adapted to seat against a relatively stationary valve element in the form of a valve seat 60 and the upper end portion 70 of the valve stem 57, which is disposed above the movable valve element 58 mounted thereon, projects through and works in a centrally arranged opening 71 which is formed in the stationary valve seat member 61 (Fig. 2).

The stationary valve element or valve seat 60 is formed as an integral part of an externally threaded tubular member 61 which is threaded into the enlarged internally threaded lower end portion 63 of a pipe 64. This pipe 64 has an upper end portion which is connected, as at 66 to the lower area of the steam zone 44 of the upper compartment 17 of the tank or boiler 11 and the pipe 64 is also connected between its ends, as at 65, to the lower area of the water zone 46 of the upper compartment 17 of the boiler 11.

A steam pressure equalizer pipe 67, which is relatively smaller in diameter than the pipe 64, has an upper end portion which opens, into the lower area of the steam zone 44 of the upper compartment 17 of the tank or boiler 11, and the lower end portion of this pipe 67 opens into the casing or housing 51 of the float valve control unit 50 by way of an opening 72 which is formed in the top wall 54 of the casing or housing 51 of the float valve control unit 50, as shown in Fig. 2.

An air inlet in the form of a hand hole 73 is provided in the lower end portion of the side wall 12 of the boiler 11, as shown in Fig. 1, to afford a supply of air to the gas burner coils 31 as well as for the purpose of enabling manual access to be had to the lower area 16 of the tank or boiler 11 for the purpose of lighting the gas burner unit 30.

In the use and operation of the new heating apparatus the same may be installed in the basement of a residence or like building and the various necessary pipe connections made as hereinbefore described. The manually operable control valve 36 may then be opened to admit water into the lower water zone 46 of the upper compartment 17 of the tank or boiler 11 until the level of water therein reaches approximately the normal water level 45. During this operation of filling the lower water zone 46 in the upper compartment 17 of the tank or boiler 11 water will flow, by gravity, by way of the branch pipe 65 and the pipe 64-63 through the central opening 71 in the valve seat 61, past the movable valve element 58, through the externally threaded tubular member 61 in which the valve seat 61 is formed and into the housing 51 of the float valve control unit 50, and thence by way of the pipe 55 into the lower area of the water jacket 26. This flow of water by gravity will continue until the water in the water jacket 26 reaches approximately the level indicated by the dotted line 74, at which time the water in the housing 51 of the float valve control unit 52 will be at a level, indicated by the dotted line 75 and corresponding to the level 74 of the water in the water jacket 26 (Fig. 1).

The manual control valves (not shown) to the

fuel supply lines 32 may then be opened to admit gas to the apertured gas burner coils 31 of the heating unit 30, and the gas emerging from the latter may be lighted by means of a match manually inserted through the combination air inlet opening and hand hole 73 in the lower portion of the side wall 12 of the tank or boiler 11 (Fig. 1). The flame and heat thus developed in the gas heating coil unit 30 will be directed against the bottom wall 28 of the water jacket 26 and will convert the water therein into steam. The steam thus generated in the water jacket 26 of the steam generating unit will pass into the lower section 38 of the pipe 37, by way of the openings or apertures 39 therein, and thence up the pipe 37 into the steam zone 44 of the upper compartment 17 of the tank or boiler 11 from which the steam will pass by way of the outlet line or pipe 21 to steam radiators in the residence or like building in which the new heating apparatus 10 is arranged. The water of condensation will return by way of the return line 18-19-20 into the lower water zone 46 of the upper compartment 17 of the boiler 11.

The normal water level 74 in the water jacket 26 of the steam generating unit 25 is automatically controlled and maintained by the float valve control unit 50. Thus it will be seen that when the common water level 74-75 in the water jacket 26 and in the housing 51 of the float valve control unit 50, respectively, reaches the desired normal level, the float 59 will rise and move the movable valve element 58 into seating engagement with the valve seat 60 and thus prevent further flow of water from the lower water zone 46 of the upper compartment 17 of the tank or boiler 11 through the water supply line 65-64-63-71-61-51-55 to the lower area of the water jacket 26 of the steam generating unit.

It will be noted that the pressure of steam accumulating in the upper area of the water jacket 26, if not counteracted, would have a tendency to act through the water in the steam jacket 26, pipe 55, and float valve housing 51 to raise the float 59 and thus maintain the movable valve element 58 in constant engagement with the stationary valve element or seat 60. However, any such tendency of the steam pressure in the water jacket 26 to create a locking action upon the float valve unit 56 is offset by the fact that the pipe 64 is connected at 66 into the lower area of the steam zone 44 of the upper compartment 17 of the tank or boiler 11 so that steam under substantially the same pressure as the steam in the water jacket 26 is supplied by the line 66-64-63-71-61 into the interior of the float valve housing 51 above the float 59 so that the steam pressure on both sides of the float 59 is thus equalized and the float 59 is free to respond only to variations in the common level 74-75 in the water jacket 26 and float valve housing 51.

It will further be noted that any tendency of the steam flowing into the float valve housing 51 by way of the line 66-64-63-71-61 to build up a steam pressure above the movable valve element 58 sufficient to maintain the movable valve element 58 in open position is offset by the action of the steam entering the upper area of the float valve housing 51, below the movable valve element 58, by way of the relatively small diameter steam pressure equalizer pipe 67.

Cold water entering the water-conducting and water-heating coil 47, by way of the inlet pipe 48, is heated by the combined action of the hot water in the water zone 46, by the steam passing

through the pipe 43, and by the steam in the steam zone 44 of the upper compartment 17 of the boiler 11. The water thus heated in the coil 47 flows, by way of the outlet pipe 49, to suitable faucets or other conveniences in a residence or the like in which the new heating apparatus 10 may be employed.

It will be noted that the sleeve or jacket 42, which surrounds the steam pipe 43, prevents the cold water flowing into the water zone 46 by way of the cold water inlet pipe 35 from coming into direct contact with the hot steam pipe 43 but still allows heat from the hot steam pipe 43 to pass through the air space between the steam pipe 43 and the jacket 42, through the jacket 42, and into the hot water-conducting and hot water-heating coils 47.

The gases of combustion from the gas heating unit 30 pass up the fume duct 34 from which they may be allowed to escape to the atmosphere.

If desired, an oil burner unit or an electrical heating unit may be substituted for the gas burner heating unit 30 shown in the drawing.

The partition 15 is preferably arched upwardly, as shown, since this form of construction enhances the resistance of the partition to the downward bending forces exerted thereon by the water in the water zone 46 and the pressure of the steam in the steam zone 44 applied upon the water in the water zone 46.

The construction and operation of the safety release valve 22, the steam gauge 23, and the rheostat pressure control unit 24 are conventional and hence require no further explanation.

It will thus be seen from the foregoing description, considered in conjunction with the accompanying drawing, that the present invention provides a new and improved heating apparatus having the novel features of construction and the desirable advantages and characteristics hereinbefore mentioned and others which are inherent in the invention.

It will also be seen from the foregoing description, considered in conjunction with the accompanying drawing, that the present invention thus accomplishes its intended objects, including those which have been pointed out hereinbefore, and others which are inherent in the invention.

I claim:

50. A heating apparatus comprising a substantially cylindrical steel boiler including a vertically extending side wall and generally horizontally extending top and bottom walls and a generally horizontally extending transverse partition extending across the interior of the said boiler between the said top and bottom walls thereof and dividing the interior of the said boiler into an upper compartment defined by the said side wall and the said top wall and the said transverse partition and including an upper steam zone and a lower water zone, and a lower compartment defined by the said side wall and the said bottom wall and the said transverse partition, said boiler having a valve-controlled cold water inlet into the said lower water zone of the said upper compartment, and having a steam outlet from the said upper steam zone of the said upper compartment, a steam-generating water jacket arranged in the said lower compartment of the said boiler below the said transverse partition, a heating unit below the said water jacket for heating water therein and converting the same into steam, a vertically extending steam-conducting pipe arranged centrally in the said boiler and including 65 the said lower end portion extending downwardly

through the said water jacket centrally thereof for the reception of steam from the said water jacket, the said steam-conducting pipe including an upper portion extending upwardly through the said transverse partition and through the said water zone and opening at its upper end into the said steam zone of the said upper compartment, a water supply line for supplying water from the said lower water zone of the said upper compartment of the said boiler into the lower area of the said water jacket, an automatically operated float valve unit arranged in the said water supply line between the said water zone and the said water jacket for automatically maintaining the water level in the said water jacket substantially constant, and means for equalizing the effective steam pressure and the effective water pressure on the said valve unit from the said upper compartment and the said water jacket, respectively.

PHILIP GUESON.
